UNITED STATES PATENT OFFICE

2,170,928

MINING MACHINE

Nils D. Levin, Columbus, Ohio, assignor to The Jeffrey Manufacturing Company, a corporation of Ohio

Application January 3, 1936, Serial No. 57,376
Renewed June 13, 1939

20 Claims. (Cl. 262—28)

This invention relates to a mining machine and more particularly to a track mounted coal cutting machine.

An object of the invention is to provide a very flexible kerf-cutting machine, which is particularly adapted to cut horizontal kerfs between wide limits, from a position adjacent a mine bottom to a great height and avoid any "blind spots" whatever between the two extreme positions.

10 Another object of the invention is to provide a kerf-cutting machine which is capable of cutting both vertical and horizontal kerfs, the latter being between wide limits without any "blind spots".

Another object of the invention is to provide a 15 mining machine including mechanism whereby the overall height of the machine may be relatively small to allow its use in low vein mines, but which may be extended to an appreciable height.

20 Another object of the invention is the provision of improved and efficient mechanism for supporting a turnover head, on a track mounted mining machine for adjustment in elevation, combined with slide thrust bearings in a compact 25 space so as to reduce to a minimum the length of the machine to thereby facilitate transportation along sharp curves of the mine track and so as to relieve such adjusting mechanism of the back thrust during rectilinear feed of the cutting 30 mechanism.

Another object of the invention is the provision of compact, improved and efficient mechanism between slide thrust bearings and the turnover head of an elongated chain kerf-cutter, 35 for adjusting the elevation of such head, combined with mechanism associated therewith for driving the kerf-cutter.

Another object of the invention is the provision of improved and efficient means comprising 40 sprocket chain gearing for adjusting the elevation of the cutter of a mining machine.

Another object of the present invention is the provision of compact, improved and efficient means comprising worm gearing and sprocket 45 and a chain drive connected thereto, for turning over at a relatively slow speed the cutter head of a mining machine and locking the head in adjusted position.

A further object is the provision in a turnover 50 head mining machine of means comprising parallel screws located between slide thrust bearings and a neck supporting the head, for adjusting the neck relative to supporting framework, and associating such means with the power transmission mechanism for driving the cutter, in such

compact relation as to reduce to a minimum the length of the mining machine.

Another object of the invention is the provision of a box-like enclosure for elevating mechanism of a kerf-cutter which shall also serve to co-operate with slide thrust bearings to form guide-ways for the cutter head of a mining machine.

A further object of the invention is the provision of turnover head mechanism for the cutting mechanism of a mining machine combined 10 with means for adjusting the turnover head mechanism and with slide thrust bearing guides in position to relieve the adjusting means of feeding pressure or back thrust.

Another object is the provision of improved 15 and efficient mechanism for reducing to a minimum the radius of arcuate feeding movement of a kerf-cutter on a turntable axis, in a mining machine in which the kerf-cutter can be adjusted on a turnover head axis, and also in parallelism 20 and at right angles to such axis.

Other objects of the invention will appear hereinafter, the novel features and combinations being set forth in the appended claims.

In the accompanying drawings:

Fig. 21 is a schematic elevational view of the mining machine showing the range of vertical cuts and the method of making said cuts between the two extreme positions.

Referring particularly to Figs. 1 and 2 of the drawings, there is seen a mining machine comprising my invention which includes a number of the elements disclosed in prior patents issued to me, such as my patent, for Coal mining apparatus, No. 1,904,489, issued April 18, 1933, and my patent, for Coal cutting machine, No. 1,867,853, issued July 19, 1932.

Certain features of the invention herein disclosed and particularly those features disclosed in detail in Figs. 11, 12 and 13, are also disclosed in full detail and claimed in my application, for a Mining machine, Serial No. 656,697, filed February 14, 1933.

The mining machine comprises a main frame 20 adapted to be mounted upon track rails 21 by wheels 22. Driving of the mining machine upon the track rails 21 at either a sumping speed or a transportation speed is provided by virtue of a truck motor 23 which is connected to said wheels 22 through appropriate drive means including the chain 24 (Fig. 10) and appropriate variable speed gearing mechanism. A reel mounted electrical cable 25 is provided for supplying electrical current to the motor 23 and to other electrical apparatus on the machine.

Mounted upon the main frame 20 for vertical adjustment in both a horizontal plane and in planes which are tilted to the horizontal, there is a turntable frame 26 adapted to carry a turntable 27. The turntable frame 26 carries rollers 28 adapted to permit rotation of said turntable 27 about a vertical axis relative to said frame 26. Vertical adjustment of the turntable frame 26 is provided by virtue of three supporting posts 29 by which said turntable frame 26 is supported upon the main frame 20 for adjustment with respect thereto. The structure of the posts 29 is illustrated in detail in Figs. 17 and 18 and is described in full detail and claimed in my above-mentioned Patent No. 1,904,489. Reference is made to that patent for a complete description 75 of the operation of these adjustable posts.

Briefly described, it may be pointed out that the turntable frame 26 is supported by a screw shaft 30 which co-operates with a second telescoping screw shaft 31. The screw shaft 31 is supported for vertical adjustment with respect to the main frame 20 by a threaded cup 32. An individually operable clutch 33, shown in detail in Fig. 17, is provided for each of the adjustable posts 29 whereby it is possible to control the elevation of one portion of the turntable frame 26 independent of any other portion thereof.

As best seen in Fig. 10 of the drawings, a continuous chain 34 is provided for operating the three adjustable posts 29. The chain 34 is driven from the motor 23 through appropriate gearing mechanism. It is evident that by engaging each of the three clutches associated with the three adjustable posts 29, all of said adjustable posts may be operated at once to provide elevation of the turntable frame 26 in a horizontal plane, while by operating the clutches 33 individually, said turntable frame 26 may be tilted universally. It should be pointed out that by employing the particular adjustable post mechanism illustrated, an extremely wide range of adjustment of the height and inclination of the turntable 27 is provided. This feature is of importance in providing for cutting of both horizontal and vertical kerfs, the former between wide limits while avoiding completely the presence of any "blind spots".

The turntable 27 is mounted upon the turntable frame 26 for rotation about an upright axis by means which may take the form disclosed in my aforementioned application Serial No. 656,697 and as illustrated in Figs. 1, 11, 12 and 13 of the drawings, or it may take the form of the means disclosed and claimed in my aforementioned Patent No. 1,867,853. Briefly described, this means, as illustrated in the drawings, comprises a motor 35 which is also the motor for driving the kerf cutter and the head elevating mechanism, which motor is provided with a shaft 36 carrying a pinion 37. The pinion 37 meshes with bevel gear 38 mounted upon a vertical shaft 39 (Fig. 3).

Eccentric mechanism 40 is provided to drive the double pawl 41 upon rotation of the shaft 39. The double pawl 41 co-operates selectively with one of the two ratchet wheels 42 or 43 to rotate the shaft 44 in a clockwise or counter-clockwise direction dependent on which of said ratchet wheels is exposed to its pawl by a controlling shield. The shaft 44 carries a worm 45 which meshes with worm gear 46, which worm gear 46 is adapted to drive gear 47 through friction clutch mechanism 48. Engagement or disengagement of said friction clutch mechanism 48 will determine whether or not the gear 47 rotates upon rotation of shaft 44. Gear 47 meshes with gear 49 which drives pinion gear 50 through shaft 51, which pinion gear 50 meshes with a large ring gear 52 rigidly attached to the turntable frame 26.

As illustrated in Figs. 11 and 13, operation of the clutch 48 may be effected through chain and sprocket drive means 53 adapted to be operated from hand wheel 54 through a pair of bevel gears 55. It will thus be evident that readily controllable means are provided for controlling the rotation of the turntable 27 with respect to the turntable frame 26 which, as illustrated in the drawings, comprises a friction controlled gear connection between the motor 35 and the ring gear 52 associated with said turntable frame 26. The speed of rotation of said turntable may be adjusted by adjustable shield controlling means 75

seen at 56 in Fig. 1, and the direction of rotation thereof may be controlled by determining which of the two ratchet wheels 42 or 43 is in operative relation with the double pawl 41. (Fig. 11.) 5 This provides for rotation of the turntable 27 in either direction and at variable speeds regardless of the direction of rotation of the motor 35 which motor is reversible for purposes hereinafter more apparent. The details of said controlling means 56 are shown in my Patent No. 1,867,853.

Referring particularly to Figs. 1, 2, 19, 20 and 21, it may be pointed out that an adjustable turn-over head support 57 is mounted upon the turntable 27 and extends forwardly therefrom, to which is adjustably mounted a turn-over head 58. The turn-over head 58 carries an adjustable cutter bar 59 adapted to support the kerf cutting chain 60.

20 It will be evident that there are three principal vertical adjustments which provide for the cutting of a plurality of horizontal kerfs illustrated in Figs. 19 and 20. For example, with the turn-over head 58 adjusted so that the cutter bar 59 extends from the bottom thereof, as illustrated in Fig. 19, it is possible to cut kerfs at any place between the extreme positions illustrated by the kerfs 61 and 62. That is, the turn-over head 58 may be adjusted vertically with respect to the adjustable turn-over head support 57, by means hereinafter described more in detail, to position the cutter bar 59 anywhere between the kerf 61 and the kerf 63. Further adjustment of the cutter bar 59 to any position 25 between the kerf illustrated at 63 and the kerf illustrated at 62 is provided by adjustment of the adjustable posts 29. By adjusting the turn-over head mechanism 58 so that the cutter bar 59 is on top thereof, kerfs may be cut between the two positions illustrated by kerfs 64 and 65, by an adjustment of the posts 29 and of the adjustable turn-over head support 57. For example, kerfs may be cut between the positions illustrated by kerfs 64 and 66 by adjustment of the 30 adjustable turn-over head support 57 and between the kerfs 66 and 65 by the additional adjustment provided by the posts 29. The kerfs 62 of Fig. 19 and the kerfs 65 of Fig. 20 are either coextensive or the former is at a higher elevation than the latter.

It is thus evident that by virtue of the adjustment provided by adjustable posts 29, adjustable turn-over head support 57, and the turn-over head 58, kerfs may be cut in any horizontal plane 35 between the kerfs illustrated at 61 and 64 in Figs. 19 and 20 without any "blind spots" whatever. Furthermore, it is possible to adjust the posts 29 so that the kerfs need not be horizontal but may be inclined to the horizontal to any reasonable degree. This provides for the removal of any dirty bands which may not be entirely horizontal.

Due to the universal mounting of the turntable 27, it will of course be evident that this inclination of the cutter bar 59 may be either 40 about a longitudinal or transverse axis, or both. By adjusting the turn-over head 58 so that the cutter bar 59 is in a vertical plane, as illustrated in Fig. 21, and then by adjusting the adjustable turn-over head support 57 and the turntable 27 45 by means of the adjustable posts 29, vertical kerfs may be cut between the extreme positions of horizontal kerfs 61 and 64.

By virtue of a further adjustment between the cutter bar 59 and the turn-over head 58, which 50 will be hereinafter described more in detail, the

cutter bar 59 may be pivoted with respect to the turn-over head 58 to any desired position where it may be locked. This adjustment may be useful to realize the full range of vertical cuts desired by the machine.

Attention is now directed particularly to Figs. 3, 4, 5, 6 and 7 which illustrate in detail the operating mechanism which provides the numerous adjustments above considered. The adjustable turn-over head support 57 comprises a frame 70 which may be bolted to the turntable 27 by bolts 71 and is adapted to extend forwardly therefrom and project downwardly, as well illustrated in Fig. 2 of the drawings. The frame 70 is of course mounted rigidly with respect to the turntable 27. Within said frame 70 there is provided a vertically adjustable frame 72 provided with guide rails 73 (Fig. 4) adapted to be guided for vertical adjustment by receiving guideways 74 of said rigid frame 70.

The adjustable frame 72 is provided with laterally extending brackets 75 and 76, one on each side, adapted to receive the threaded square nuts 77 and 78, respectively and to prevent rotation thereof. The brackets 75 and 76 are provided with upper and lower webs, each bifurcated, whereby the nuts 77 and 78, respectively, may be readily removed by outward lateral movement, as seen in Fig. 4, but are restricted against vertical movement either upwardly or downwardly.

Received by the nuts 77 and 78 and in threaded relation therewith is a pair of upstanding screw shafts 79 and 80, respectively. Said screw shafts 79 and 80 are carried by the rigid frame 70 by appropriate journal bearings 81 and 82, 35 respectively, adjacent the bottoms thereof and journal bearings 83 and 84 adjacent the tops thereof.

Pin and plate type thrust bearings are provided at 85, 86, 87 and 88 for transferring the 40 vertical forces received by screw shafts 79 and 80 to the rigid frame 70. It will be evident, of course, that upon rotation of the screw shafts 79 and 80 the vertically adjustable frame 72 will be adjusted vertically with respect to the rigid 45 frame 70.

As best seen in Figs. 3 and 6, the adjustable frame 72 carries a bottom plate 89 adapted to support a bevel gear 90 upon anti-friction bearing 91 which bevel gear 90 is keyed rigid with a 50 quill 92 splined to a vertically extending spline shaft 93. A cup 94 is also carried by the adjustable frame 72 and with the bottom plate 89 supports the quill 92 for rotation by appropriate journal bearings 95 and 96, respectively.

It will be evident, of course, that the spline shaft 93 co-operates with the quill 92 to allow vertical adjustment of said adjustable frame 72 relative to said rigid frame 70 while transferring rotary motion from the shaft 93 to the bevel gear 90 in any position of adjustment of said adjustable frame 72. The spline shaft 93 is mounted upon the rigid frame 70 by an anti-friction ball bearing 97 adapted to fit in a cup 98. A dished sprocket 99 is provided for driving the shaft 93, a dish-shaped construction being employed to house the bearing 97 while maintaining a minimum overall height of the adjustable turn-over head support 57. A pin type thrust bearing 100 may be provided between the 65 sprocket 99 and the removable cover 101 of said adjustable turn-over head support 57.

Power for driving the shaft 93 is derived from the sprocket 102 (Fig. 3) driven from shaft 39 through the intermediary of a chain 103. A jaw 75

type clutch 104 is provided for effecting engagement or disengagement of the sprocket 102 and the shaft 39. As best seen in Fig. 1 of the drawings, operating mechanism 105 is provided for controlling the clutch 104. This clutch 104 is provided so that rotation of the turntable 27 may be effected without operating the gear train including shaft 93.

To effect rotation of the screw shafts 79 and 80 and thereby to control adjustment of the vertically adjustable frame 72 with respect to the rigid frame 70, a gear 106 (Fig. 6) is keyed to the shaft 93 and drives a gear 107 rigidly mounted on a clutch element 108, said gears 106, 107 being connected through the intermediary of an idler gear 109. It may be pointed out that the gear 109, as seen in Fig. 9, is removably mounted on a web of the rigid frame 70 by an anti-friction roller bearing 110 carried by a washer 111 on a stud shaft 112, which shaft 112 is welded to said web of frame 70.

The upper end of the screw shaft 80 has keyed thereto a quill 113 which carries at its upper end a sprocket 114. Sprocket 114 is adapted to drive a sprocket 115 carried by a quill 116 keyed to the upper end of screw shaft 79 whereby the screw shafts 79 and 80 would rotate in unison. Said sprockets 114 and 115 are driven through chain 117 which is kept in proper tension by adjustable tensioning mechanism 117' which also performs the additional function of keeping the chain 117 out of contact with the sprocket 99.

To provide drive mechanism for the screw shaft 80 I provide a clutch element 118 which is feathered on the screw shaft 80 for vertical adjustment with respect thereto, which clutch element carries a friction surface 119 adapted to co-operate with the clutch element 108. A shipper 120 adapted to be operated by a shaft 121 is provided for controlling the engagement or disengagement of said clutch elements 108 and 118. Shaft 121 is adapted to be rocked upon the operation of handle 122 through the intermediary of an adjustable connecting link 123 and lever 124. It will be evident that upon lifting the handle 122, as viewed in Fig. 8, the shaft 121 will be rocked in a counter-clockwise direction to lift the clutch element 118 and to engage the friction surface 119 with the clutch element 108.

It will thus be evident that a driving connection may be provided at will between the shaft 93 and the screw shafts 79 and 80 to effect vertical adjustment of the vertically adjustable frame 72 with respect to the rigid frame 70. It will be evident, of course, that the nuts 77 and 78 co-operate with the screw shafts 79 and 80 to hold the vertically adjustable frame 72 in any adjusted position.

As best seen in Fig. 3 of the drawings, the vertically adjustable frame 72 is provided with an integral neck 125 which forms a drum type support for the turn-over head 58. Within the neck 125 there extends a horizontal shaft 126 supported upon anti-friction bearings 127 and carrying at its opposed ends bevel gears 128 and 129. The bevel gear 128 meshes with bevel gear 90 and thus the shaft 126 is driven through the train of gears including the shaft 93.

The turn-over head 58 comprises a frame 130 having a supporting collar 131 adapted to be supported by the neck 125 through an interposed journal bearing 132. It will thus be evident that the turn-over head 58 is mounted for rotary adjustment with respect to the adjustable turn-

over head support 57 about a longitudinal and horizontal axis.

As best seen in Fig. 14 of the drawings, in order to prevent the inadvertent removal of the turn-over head when the mining machine is moved rearwardly to withdraw the cutter bar 59 from a kerf, a locking mechanism in the form of an H-shaped bracket 133 is provided which is carried by the collar 131 and extends into a circumferential groove 134 in the neck 125. It may be pointed out additionally, that a gear casing 135, as best seen in Fig. 7, also has a flange 135' which projects into the groove 134 to aid the work of bracket 133. Within the groove 134 there is also provided a split worm gear 136 rigidly attached to the neck 125 by machine screws 137.

Within the frame 130 of the turn-over head 58 there is provided a shaft 138 mounted for rotation by anti-friction bearings 139 and 140. The bearing 139 is actually carried by the adjustable plate 141 which is adjustably mounted with respect to the frame 130 for pivotal movement on the axis of the shaft 138 by journal bearing 142. The plate 141 is held to said frame 130 by a removable ring 143 having a retaining flange, and held to the frame 130 by screws 144. The plate 141 carries the cutter bar 59 and of course provides for the adjustment of said cutter bar 59 with respect to the turn-over head 58 about the axis of said shaft 138, as aforesaid. Bearing 140 is actually carried by removable cover 130' of frame 130.

A locking pin 145 is carried by the frame 130 and is adapted to co-operate with any one of a plurality of apertures 146 carried by the plate 141 to lock the cutter bar 59 in any selected position of adjustment. The pin 145 may be operated from either side of the cutter head by handles 147 carried at the ends of shaft 148 adapted to control the operation of pin 145 upon rocking movement, through the shipper 149.

The shaft 138 carries a sprocket 150 which co-operates with the cutter chain 60 to drive said cutter chain around the cutter bar 59 to perform a kerf cutting operation. The direction of travel of the cutter chain will be determined by the direction of rotation of the reversible motor 35. Rotation of the shaft 138 to drive the sprocket 150 is provided through the bevel gear 151 mounted on and keyed to a clutch element 153 provided with jaws 154. A quill 152, loosely carried on the upper end of the shaft 138, is keyed to said clutch element 153.

Feathered on the shaft 138 is a co-operating clutch element 155 provided with jaws 156 adapted to engage the jaws 154 when in one position of adjustment. It will be evident that upon the engagement of the jaws 154 and 156, the power from the shaft 126 will be transferred to said shaft 138.

For operating the clutch element 155 I provide a shipper 157 which may be operated from a shaft 158 controlled by levers 159 (Fig. 5) on either side of the turn-over head 58. To provide power means for turning over the head 58 about the axis of the shaft 126, the quill 152 is keyed to a sprocket 160 by a horizontal key 161 comprising a safety shear pin (see Fig. 16) which may be retained in place on said quill by a washer 162 (Fig. 3). This particular construction is provided to maintain at a minimum the thickness of the hub of the sprocket 160 whereby the distance from the axis of the shaft 126 to the top of the turn-over head 58 may be maintained at a minimum. This is to allow for the entry of the min- 75

ing machine into a relatively low vein mine when the turn-over head is in the position illustrated in Fig. 3.

As best seen in Fig. 5 of the drawings, the sprocket 160 is adapted to drive a sprocket 163 through a chain 164 which also travels over an adjustable tensioning mechanism 165 including a roller 166. The sprocket 163 carries clutch jaws 167 which are part of a clutch mechanism illustrated in Figs. 7 and 15 which control the turning over of the turn-over head 58. This clutch is a novel arrangement and is provided to maintain a minimum height of head for the reasons above set forth.

The sprocket 163 is journaled on a quill 168 which carries laterally extending jaws 169. The quill 168 is also keyed to shaft 170 which is journaled in the gear case 135 by anti-friction bearings 171. There is no relative movement between the sprocket 163 and the quill 168 along the axis of the shaft 170. Therefore to provide an operative connection between the two I employ a collar 172 provided with dogs 173 adapted to be moved along the axis of the shaft 170 and to engage the jaws 167. It will be evident that the dogs 173 are in permanent engagement with the jaws 169 of the quill 168. To provide the aforementioned movement of the collar 172, I provide a shipper 174 which may be operated from a lever 175 (Fig. 5) controllable by handles 176, one on each side of the turn-over head 58, which are carried on shaft 177 which is provided with a crank or eccentric 178 to pivot the lever 175 about its pivot point 180, upon rotary movement of said shaft 177.

It will be evident that by controlling either of the handles 176, the shaft 170 may be placed in operative relation to the motor 35. Said shaft 170 carries a worm 181 which co-operates with worm gear 136 to provide rotary movement of the turn-over head 58 about the axis of shaft 126. The worm 181 will have such a pitch that the turn-over head 58 will be locked in any position to which it is adjusted. It is evident that a complete revolution of the turn-over head about the axis of the shaft 126 may be effected. However, said turnover head may be stopped in any desired position of adjustment where it will be automatically retained.

A removable cover plate 182 is provided to enclose the chain 164 and associated mechanism, and when the turn-over head 58 is in the position illustrated in Fig. 3 and is adjusted to its maximum height, said cover plate 182 will be in substantial alignment with the cover plate 101 of the adjustable turn-over head support 57. As a consequence the turn-over head 58 will not increase the height of the machine over that required by the adjustable turn-over head support 57.

As best illustrated in Figs. 1 and 5 of the drawings, the adjustable turn-over head support 57 is attached to the turntable 27 by the bolts 71 which extend through elongated slots 183. Said slots 183 provide for the longitudinal adjustment of said adjustable turn-over head support 57 with respect to the turntable 27. This adjustment may be effected by the abutment screw 184 (Fig. 3) which is threaded into the rigid frame 70 and abuts the turntable 27. A wrench receiving aperture 185 is provided whereby the stud 184 may be adjusted.

It may be pointed out additionally that a protecting apron 186 (Fig. 2) is provided near the sprocket 150 to protect the cutter chain as it rounds said sprocket 150.

The mode of operation of the device will be obvious from a consideration of Figs. 19, 20 and 21 when considered in connection with the above detailed description of the device. For example, if a bottom horizontal kerf is to be cut, the turntable 27 may be moved to its lowermost position and the turn-over head 58 lowered to its lowest position with respect to the adjustable turn-over head support 57, with the cutter bar 59 on the bottom of said turn-over head 58. In this position the machine may be driven forward at a sumping speed while sumping the cutter bar 59 into the room face to cut the bottom kerf 61. While in the horizontal position, the cutter bar 59 may be swung by swinging the turntable 27 in either direction upon its upright axis. In addition to making the bottom cut, a horizontal kerf may be cut at any elevation between the bottom kerf 61 and the kerf illustrated at 62 in Fig. 19 without turning over the head 58. This is provided by the vertical adjustment of the head 58 with respect to the adjustable turn-over head support 57 and by the adjustment of the turntable 27 with respect to the frame 20 by means of the adjustable posts 29.

By turning over the head 58, horizontal kerfs may be cut at any elevation between the top kerf 64 illustrated in Fig. 20 and the intermediate kerf 65. Kerf 62 will be at an elevation at least as high as, and preferably higher than, kerf 65.

Two parallel vertical kerfs may also be cut parallel to the tracks at any height between the top kerf 64 and the bottom kerf 61. To cut one such vertical kerf, the turn-over head 58 will be adjusted by worm 181 and worm gear 136 until the cutter bar 59 is in a vertical position where it will be locked by the self-locking worm 181 and worm gear 136, as illustrated in Fig. 21. Adjusting posts 29 will then be operated, by elevating the front part of turntable 27 more than the rear part, until the cutter bar 59 slopes upwardly as illustrated in full lines in Fig. 21. The machine is then driven along its tracks at a sumping speed, as provided by the drive means therefor operating wheels 22 from motor 23. The cutter chain 60 will, of course, be operated to cut the kerf. This action will continue until cutter bar 59 is in the position illustrated in full lines in Fig. 21. The screws 79 and 80 of the adjustable turn-over head support 57, would then be operated, from

their previously positioned adjustment for maximum height of the turn-over head 58 to the minimum height thereof. Thus the cutter bar 59 would move downwardly in a parallel position, under power, continuing the cutting of the kerf. Thereafter the forward adjusting posts 29 will be lowered to tilt the cutter bar 59 downward, thus continuing the downward movement of said cutter bar 59, under power. If necessary to complete the cut, the rear adjusting post 59 will be elevated from its previous minimum low position to tilt the cutter bar 59 even further with its free end in a very low position. Thereafter, the mining machine is moved away from the mine face at a tramping speed, to complete the bottom cut of the kerf. It will be evident that by the combined action of the tiltable turntable 27 and the adjustable turn-over head support 57 vertical kerfs between extreme heights may be cut. Two such kerfs may be cut by positioning the turn-over head 58 with the cutter bar 59 on opposite sides of the axis of rotation of said turn-over head 58, with said cutter bar 59 parallel to the mine tracks 21.

It is thus obvious that a very flexible machine 75

has been produced which will cut horizontal kerfs at any height from the floor to the ceiling without "blind spots" which may cover a range of as high as seven feet. Two vertical kerfs may also be cut along lines parallel with the mine track.

It may be pointed out additionally that the vertical adjustment of the turn-over head 58 provided by the adjustable screws 79 and 80 of the turn-over head support mechanism 57 is sufficient so that the cutter bar 59 may cut a kerf in any horizontal plane between that which it would cut when the head 58 is in the position illustrated in Fig. 19 and that which it would cut were the head 58 turned over and the cutter bar 59 on the top thereof with said head 58 in the lowermost position with respect to the adjustable turn-over head support 57. That is, the range provided by screws 79 and 80 is as great as the distance between parallel kerfs cut by merely turning the head over from a position where the cutter bar is on the bottom thereof to a position where it is on the top thereof.

Another feature of my machine lies in the fact that a vertical kerf of appreciable height may be cut without tilting the turntable 27 providing a kerf with a rectilinear vertical back which is an ideal kerf for shooting. For example, the turntable is raised to its topmost position and the cutter bar 59 placed in a vertical position. With the plane of kerf cutter 59 vertical the head 58 is elevated to its highest position. Prior to its elevation as aforesaid cutter bar 58 is preferably swung about the axis of shaft 138, and when raised the front thereof is adjacent the mine roof. This provides clearance between the head 58 and the mine roof. The cutter bar 58 is then sumped in, cutting a vertical kerf. This is followed by rectilinear movement of the cutter bar 59 downwardly by adjusting the turntable 27 and the head 58 downwardly, preferably successively.

When the turntable 27 and the head 58 are in their bottom-most positions, pin 145 is released and either the turntable 27 or head 58, or both, elevated while the cutter bar 59 swings about the axis of shaft 138. This is continued until the axis of the cutter bar 59 extends downwardly a desired amount where it is locked by pin 145. This is followed by a lowering of the previously elevated turntable 27 or head 58, until the vertical kerf is completely cut between the roof and mine floor. This produces a vertical kerf having a rectilinear, rather than a curved, back which is ideal for shooting as there is a minimum tendency to form ledges.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In a mining machine, the combination with a main frame, of a kerf cutting mechanism, means for supporting said cutting mechanism from said frame for vertical adjustment comprising a rigid frame connected to said main frame, an adjustable frame vertically adjustable relative to said rigid frame, nuts carried by said adjustable frame on two sides thereof, threaded screw shafts carried by said rigid frame and co-

operating with said nuts to produce relative movement between said rigid frame and said adjustable frame upon rotation of said shafts, a splined shaft carried by said rigid frame and extending through said adjustable frame, drive means for said kerf cutting mechanism comprising a sprocket on said splined shaft and a gear carried by said adjustable frame and driven by said splined shaft, said sprocket being dished to house an anti-friction bearing which supports said splined shaft on said rigid frame, and means for driving said screw shafts from said splined shaft, said means including sprockets on said screw shafts, a chain connecting said sprockets, means for tensioning said chain and guiding it around said dished sprocket, and gears and a clutch connecting said splined shaft and one of said screw shafts.

2. In a mining machine, the combination with a main frame, of a turn-over head supported from said main frame on a neck extending longitudinally from said main frame, a collar on said head pivotally mounted on said neck, said neck being grooved peripherally, a worm gear mounted in said groove, a worm co-operating with said gear and carried by said head and which when rotated causes rotation of said head about said neck, a retaining bracket carried by said collar and projecting into said groove to prevent longitudinal movement of said head relative to said neck, and means for operating said worm.

3. In a mining machine, the combination with a main frame, of a turn-over head supported from said main frame on a neck extending longitudinally from said main frame, a collar on said head pivotally mounted on said neck, said neck being grooved peripherally, a worm gear mounted in said groove, a worm co-operating with said gear and carried by said head and which when rotated causes rotation of said head about said neck, a housing for said worm carried by said head and projecting into said groove to prevent longitudinal movement of said head relative to said neck, and means for operating said worm.

4. In a mining machine, the combination with a main frame, of a turn-over head supported thereby on a neck extending longitudinally therefrom, a collar on said head journaled on said neck, a worm gear on said neck, a co-operating worm carried by said head, a worm shaft, means for driving said worm shaft to rotate said head including a clutch, said clutch comprising a quill keyed to said shaft, a sprocket gear journaled about said quill for free rotation relative thereto, jaws carried by said quill and gear, and means including interlocking dogs movable into and out of position to effect a driving bridge between said jaws, said gear and quill being fixed against axial movement.

5. In a mining machine, the combination with a main frame, of a supplementary frame adjustable with respect thereto and supported thereby, a flat kerf cutter, a turnover head supporting said kerf cutter, means supporting said turnover head comprising a neck extending from said supplementary frame and a sleeve extending from said turnover head, a worm gear attached to said neck and protected by said sleeve, a worm meshing with said worm gear and movable with said turnover head, and power means for driving said worm including chain and sprocket means carried by said turnover head.

6. In a mining machine, the combination with

5 a frame, of a flat kerf cutter, means for mounting said kerf cutter on said frame comprising a turnover head, means for adjusting said turnover head vertically relative to said frame, power means for turning said head on its axis and for adjusting it vertically, said power means including a pair of chain and sprocket drives, one carried by said turnover head, the other by said frame.

10 6. In a mining machine, the combination with a frame, of a turnover head mounted on said frame, a flat kerf-cutter mounted on said head, power means for turning over said head, said power means including a worm gear, a meshing worm, and chain and sprocket means all mounted on said head, and means effecting an enclosure of said power means on said head.

15 7. In a mining machine, the combination with a frame, of a bearing neck extending substantially horizontally from said frame, a turnover head including a sleeve journaled on said neck, a cutter bar attached to said head, a cutter chain on said cutter bar, means for turning over said head comprising a worm gear on said neck and protected by said sleeve, a worm mounted on said head for movement therewith, power drive means for said worm and said cutter chain comprising a shaft mounted for rotation in said head, chain and sprocket means 20 connecting said shaft to said worm, and means enclosing said chain and sprocket means.

25 8. In a mining machine, the combination with supporting framework, of a neck extending therefrom, cutting mechanism, a head for carrying said cutting mechanism, a cylinder journaled on said neck, means for rotarily adjusting said cylinder on said neck to vary the position of the cutting mechanism, a tongue and groove interlocking connection between said cylinder and said neck intermediate the ends of the latter.

30 9. In a mining machine, the combination with supporting framework, of a neck extending therefrom, cutting mechanism, a head for carrying said cutting mechanism, a cylinder connected to said head and journaled on said neck, a worm wheel in an annular groove in said neck, a tongue on the said cylinder projecting into said groove to prevent axial displacement of the cylinder relatively to said neck, means 35 connected to said worm wheel to drive the same and adjust the head arcuately, and means for operating said cutting mechanism.

35 10. In a mining machine, the combination with a frame, of a supporting bearing mounted thereon, a kerf-cutter, mechanism mounting said kerf-cutter on said bearing for arcuate adjustment on a horizontal axis relative to said frame, power-transmission mechanism comprising a driven shaft, and means comprising chain and sprocket gearing carried by said mounting mechanism and connected to said shaft to effect such arcuate adjustment of said kerf-cutter on said horizontal axis.

40 11. In a mining machine, the combination with a frame, of a cutter-head therefor, a turret frame for supporting said cutter-head and said kerf-cutter, a bearing for supporting said turret frame for arcuate adjustment on a horizontal axis, power-transmission mechanism extending through said bearing to said kerf-cutter to drive the latter, said power-transmission mechanism comprising a transverse shaft, and means comprising sprocket chain gearing on said turret frame and connected to said shaft for operation thereby to

45 effect such arcuate adjustment of said kerf-cutter on said horizontal axis.

50 12. In a mining machine, the combination with supporting framework, of a bearing carried thereby, a chain kerf-cutter, a cutter-head for said kerf-cutter, a turret frame for supporting said cutter-head and said kerf-cutter and mounted on said bearing for arcuate adjustment relative to said framework, power-transmission mechanism extending from said framework through said bearing and through said turret frame to said kerf-cutter to drive the latter, said power-transmission shaft comprising a transverse shaft extending at right angles to the plane of said chain kerf-cutter, supplemental power-transmission mechanism comprising sprocket chain gearing connected to said transverse shaft and mounted on said turret frame for effecting such arcuate adjustment of the kerf-cutter, and a clutch for controlling at 55 will the transmission of power from said transverse shaft to said supplemental power-transmission mechanism.

60 13. In a mining machine, the combination with a chain kerf-cutter, of means comprising a turret frame for supporting said kerf-cutter, said turret frame having a rearwardly extending cylindrical collar, a bearing for said cylindrical collar, framework for supporting said bearing in stationary position, a worm gear on said bearing within said collar, power-transmission mechanism connected to said kerf-cutter to drive the same, and supplemental power-transmission mechanism branching from said first-named power-transmission mechanism to said worm gear to effect arcuate adjustment of said turret frame and said kerf-cutter on the axis of said bearing.

65 14. In a mining machine, the combination with a chain kerf-cutter, of means comprising a turret frame for supporting said kerf-cutter, said turret frame having a rearwardly extending cylindrical collar, a bearing for said cylindrical collar, framework for supporting said bearing in stationary position, worm gearing comprising a non-rotatable worm wheel on said bearing within said collar for effecting rotation of the turret to adjust the position of said kerf-cutter, power-transmission mechanism connected to said kerf-cutter to drive the same, and supplemental power-transmission mechanism branching from said first-named power-transmission mechanism to said worm gearing to effect arcuate adjustment of said turret frame and said kerf-cutter on the axis of said bearing.

70 15. In a mining machine, the combination with a main frame, of a turnover head supported from said main frame on a neck extending longitudinally from said main frame, a collar on said head pivotally mounted on said neck, said neck being grooved peripherally intermediate its ends, worm gearing for rotating said head about said neck, a retaining bracket carried by said collar and projecting into said groove to prevent longitudinal movement of said head relative to said neck, and means for operating said worm gearing.

75 16. In a mining machine, the combination with a supporting frame having a depending extension at its outer forward end, of a supplemental frame, cutting mechanism carried by said supplemental frame, rectilinear guideway mechanism extending vertically between the top and bottom portions of said depending extension for movement of said supplemental frame over a wide range extending to the bottom of said depending extension, mech- 75

- anism comprising spaced-apart vertical rotatable screws located adjacent to and in front of said rectilinear guideway mechanism for adjusting the elevation of said supplemental frame together with the cutting mechanism carried thereby vertically along said extension, and power-transmission mechanism extending from said main frame to and along said supplemental frame to said cutting mechanism to drive the same and comprising a vertical splined shaft suspended from the main frame and extending through said supplemental frame with its lower end free and unobstructed when the cutting mechanism is elevated, said splined shaft being always in driving connection with power-transmission gearing carried by said supplemental frame, the construction and arrangement being such that at the various elevations of the cutting mechanism the rectilinear guideway mechanism shall be adapted to act as thrust bearing mechanism during rectilinear feed of said cutting mechanism to relieve said shaft and said screws of feeding back thrust and the lower free end of the shaft shall afford an open space below and surrounding the same between said screws for free movement of the supplemental frame along the screws to a lowermost limit of adjustment while said shaft is still maintained in driving relation to the gearing on the supplemental frame.
18. In a mining machine, the combination with a main frame having a depending extension, of a supplemental frame, a kerf-cutter carried by said supplemental frame to move bodily therewith, tongue and groove interlocking connections between said supplemental frame and said depending extension to enable said supplemental frame to slide vertically along such depending extension, means comprising spaced-apart nut and screw elements on said depending extension and connected to said supplemental frame to adjust the elevation of the latter together with said kerf-cutter, and power-transmission mechanism between said main frame and said kerf-cutter to drive the same in the various elevated positions of the latter and comprising a splined shaft suspended from said main frame to extend through said supplemental frame while in driving connection with transmission gearing on said supplemental frame with the lower end of the splined shaft in open space when the supplemental frame is elevated, such open space being between the lower ends of the elevating screws to afford freedom of movement of the supplemental frame to its lowermost limit of travel and projecting below the depending extension.
19. In a mining machine, the combination with a supporting frame having a depending extension at its forward end, inwardly extending supports at the lower ends of the sides of said depending extension with an open space between said supports, spaced-apart elevating screws journaled at their lower ends to said supports, nuts threaded on said screws, a supplemental frame carried on said nuts, a kerf-cutter carried by said supplemental frame, power-transmission mechanism comprising a shaft suspended from said main frame to extend through said supplemental frame into said open space and splined for connection to gearing on said supplemental frame and connected to said kerf-cutter to drive the same, and interlocking guiding mechanism between said supplemental frame and said depending extension to serve as thrust bearing mechanism when the kerf-cutter is fed rectilinearly into the mine vein and to retain the supplemental frame connected to such depending extension when the kerf-cutter is pulled out of the mine vein, thereby relieving the shaft and the screws of such feeding and pulling thrusts.
20. In a mining machine, the combination with a main frame having a depending extension at its forward end, of a supplemental frame, mechanism for guiding the rear end of said supplemental frame along the rear inner wall of said depending extension, spaced-apart elevating screws, step bearings for the lower ends of said elevating screws at the lower ends of the sides of said depending extension, journal bearings for the upper ends of said elevating screws, nuts threaded on said elevating screws and connected to said supplemental frame to carry the latter, the space between the said step bearings and in front of the lower inner wall of the depending extension being open for receiving the supplemental frame when lowered to project from the lower end of said depending extension, a splined shaft suspended from said main frame to extend through said supplemental frame, the lower end of said shaft being free and unobstructed to extend into said open space when the supplemental frame is elevated, power-transmission gearing carried by said supplemental frame and connected to said kerf-cutter, and means on the main frame for driving said splined shaft for effecting driving of said kerf-cutter in the various elevated positions of the latter as well as in its lowermost position when the supplemental frame is in said open space projecting below the depending extension.
